UNITED STATES PATENT OFFICE

GEORGE F. BEACH, OF PHILADELPHIA, PENNSYLVANIA, ASSIGNOR, BY MESNE ASSIGNMENTS, TO RYAN, SCULLY & COMPANY, OF PHILADELPHIA, PENNSYLVANIA, A CORPORATION OF DELAWARE

FURNACE CONVEYER

Original application filed April 8, 1926, Serial No. 100,681. Divided and this application filed June 1, 1927. Serial No. 195,766.

My invention relates to furnace equipment, and it has for one object the provision of a conveyer particularly adapted for use in high-temperature furnaces of the continuous type.

Another object of my invention is to provide a conveyer wherein the work-supporting surface thereof comprises the upper edges of a plurality of overlapping blades.

10 A further object of my invention is to provide conveyer mechanism comprising a flexible belt and a plurality of attachments therefor provided with overlapping work-supporting blades, the blades being normal to the belt by presenting an inclined face to the line of movement of the belt.

A still further object of my invention is to provide means, whereby the flexible belt portion of the conveyer may be shielded 20 from the direct heat of the furnace, as well as subjected to the effect of cooling means.

Other objects and applications of my invention, as well as details of construction and operation, whereby my invention may be practiced, will be apparent more fully hereinafter, when taken in connection with the accompanying drawings, wherein

Fig. 1 is a longitudinal sectional view of the drawing furnace, illustrating the radial 30 blade conveyer for carrying the treated articles received from the quenching tank through said drawing furnace to skids at the discharge end thereof;

Fig. 2 is an end elevational view of the 35 drawing furnaces illustrated in Fig. 1;

Fig. 3, is a transverse sectional view taken on the line 3—3 of Fig. 1;

Fig. 4 is an enlarged detail view of one 40 of the conveyer chains and associated parts;

Fig. 5 is an enlarged detail side elevational view of the conveyer chain of Fig. 4, and

Fig. 6 is a detail top plan view of the chain attachment shown in Fig. 5.

As illustrated in Fig. 1, the axles or other 45 articles under treatment may be moved from a quenching tank by means of a conveyer 13 of the sprocket-chain type. The axles passing over the upper end of the conveyer 13 are guided by means of a slide 77 onto an outer end 78 of a conveyer. The latter

enters a furnace 11 through an inlet opening 79, passing through a heated chamber section 81, a discharge outlet 14, around supporting sprocket mechanism 82, through a cooled section 83 of the furnace 11 and finally 55 around sprocket mechanism 84 positioned externally of the furnace but adjacent to the inlet opening 79. In the passage of the axles over the slideway 77, they are automatically turned, assuming the position shown in Fig. 60 2, wherein the yokes 23 instead of extending downwardly now extend horizontally, so that all parts of the axle may be positioned in the same heat zone and a uniform temperature 65 thereby acquired.

The conveyer 12 for carrying the axles in such horizontal position through the drawing furnace 11, is particularly illustrated in Figs. 3 to 6, inclusive and comprises a pair of spaced link belts 85 and 86. The sprocket mechanism 82 at the discharge end of the furnace 11, comprises a pair of spaced sprocket wheels 87 and 88 which respectively support the outer ends of the link belts 85 and 86 and are mounted on a common shaft 89. The latter may be driven by a sprocket wheel 91 and chain 92 from a driven sprocket wheel 93. The sprocket mechanism 84 at the inlet end of the furnace 11 is similar to that just described. 70 75 80

Experience has shown that the portion of the link belts 85 and 86 in the heated chamber section 81 must be protected from the intense heat, otherwise the belts stretch to the extent of rendering the conveyer 12 as a 85 whole inoperative. Accordingly, I provide guards 94 and 95 for the portions of the link belt 85 and 86 respectively positioned within the heated chamber 81. Each of the guards comprises a pier 96 extending the length of 90 the furnace and it is provided with an inner passage 97 having a relatively narrow elongated slot 98.

The portion of the link belt which extends through the chamber 97 may be suitably supported within by means of a member 99 of the form particularly disclosed in Figs. 4, 5 and 6. Each member comprises a base portion 101, which is riveted to a link of the belt, and downwardly spaced end portions 100

102 and 103 which slidably engage spaced supporting tracks 104 and 105 formed on a base portion 106 of the chamber 97, respectively. Projecting vertically from the base portion 101 through the slot 98 is a blade 107 which is angled with respect to the length of the belt and positioned in overlapping relation to the similar member on, say, a succeeding link of the belt. Since 108 and 109 of the blade 107 are flared outwardly from the base member 101, so that a relatively wide blade is formed at the upper end thereof forming a supporting edge 111. The members 99 are so positioned that, as they pass around the sprocket mechanism 82 at the discharge end of the furnace 11, they do not separate sufficiently to permit an axle to drop therebetween but rather provide a continuous supporting surface. The axles passing through the discharge outlet 14 of the furnace 11 may be conveyed therefrom by spaced skids 15 terminating in a receptacle 114.

The portion of the chain disposed within the chamber 97 may be maintained at a desired temperature by a pair of longitudinally extending cooling pipes 115 and 116. The cooling effect of these pipes is limited to the chamber 97 by reason of the relatively small dimensions of the slot 98 and the fact that the blades 107 extend well above the belt guard 94 into the furnace passage 81.

Considering the operation of my apparatus, the movement of the sprocket chain conveyor 76 carries the axles out the quenching tank and deposits the same on the conveyor 12, causing them to assume a horizontal position, wherein the yokes 23 are in substantially the same plane as the body portion 22. After being carried through the drawing furnace 11 by the conveyor 12, the axles are finally deposited on the skids 15 leading to a cart or other receptacle 114.

While I have shown only one embodiment of my invention, for the purpose of describing the same and illustrating its principles of construction and operation, it is apparent that various changes and modifications may be made therein without departing from the spirit of my invention, and I desire, therefore, that only such limitations shall be imposed thereon as are indicated in the appended claims or as are demanded by the prior art.

I claim:

- 65 1. A furnace conveyer comprising a flexible belt, and a plurality of attachments therefor providing successive overlapping blades, the upper edges of which are adapted to constitute supporting surfaces, said blades being twisted to present an inclined face to the line of movement of the belt.
- 66 2. A conveyer belt comprising a plurality of relatively movable overlapping blades, said blades being normal to the plane of the belt but angled so as to present an inclined

face to the direction of movement of the belt, the upper edges of the blades constituting a supporting surface.

3. A conveyer comprising a link belt, certain links of which are provided with attachments having blade portions located above and extending across the said link belt, the latter forming an acute angle with respect to the line of action of the belt. 70

4. A flexible belt having a plurality of independently movable attachments provided with shoulders and blade portions, the latter being transversely disposed with respect to the line of movement of the belt, said shoulders constituting supports for the belt. 75

5. A belt comprising a plurality of pivotally connected elements forming a flexible belt, and a plurality of attachments for said elements having blades disposed at an angle across the belt and supporting shoulders, the latter serving to support an intermediate portion of the belt. 80

6. A chain, a plurality of attachments for said chain, provided with spaced supporting shoulders, said attachments having work-supporting blades extending transversely of the length of the chain, and relatively fixed cooling means in operative relation to said attachments. 90

7. The combination with a chain, of a plurality of attachments for supporting said chain intermediate the ends of the chain, said attachments having work-supporting blades, and relatively fixed cooling means in operative relation to said attachments and said chain. 95

8. A conveyer comprising a flexible belt, a plurality of attachments for said belt having supporting shoulders and work-supporting blades, and relatively fixed cooling means in engagement with said supporting shoulders. 100

9. A furnace conveyer comprising a belt and a plurality of attachments for said belt, said attachments comprising base portions adapted to be secured to the belt, shoulders adapted to afford said belt an intermediate support and work-supporting blades. 110

10. A furnace provided with a pier having enlarged and restricted recesses, a belt positioned in said enlarged recess and provided with a blade extending from said pier through said restricted recess, and relatively fixed cooling means for said belt positioned in said enlarged recess. 115

11. A furnace conveyer comprising a plurality of base elements movable substantially horizontally in the furnace, and a substantially vertically extending blade carried by each base element and arranged with its upstanding edges overlapping those of adjacent blades, the top edges of said blades constituting an article-supporting surface. 125

12. A furnace conveyer comprising a plurality of base elements movable substantially 130

horizontally in the furnace, and a substantially vertically extending blade carried by each base element and disposed at an angle with respect to the line of movement of the base element, upstanding edges of adjacent blades overlapping and the upper edges of said blades constituting an article-supporting surface.

13. A furnace conveyer comprising a plurality of base elements movable substantially horizontally in the furnace, a substantially vertically extending blade carried by each base element and arranged with its upstanding edges overlapping those of adjacent blades, the top edges of said blades constituting an article-supporting surface, and means for operatively connecting said base elements.

14. A furnace conveyer comprising a plurality of base elements movable substantially horizontally in the furnace, a substantially vertically extending blade carried by each base element and arranged with its upstanding edges overlapping those of adjacent blades, the top edges of said blades constituting an article-supporting surface, and means for supporting said base elements.

15. A furnace conveyer comprising a plurality of base elements movable substantially horizontally in the furnace, a substantially vertically extending blade carried by each base element and arranged with its upstanding edges overlapping those of adjacent blades, the top edges of said blades constituting an article-supporting surface, and means for moving said base elements as a unit through the furnace.
